UNITED STATES PATENT OFFICE.

HUGHY PERCYVILL AKERS, OF CRISMAN, INDIANA.

SPREADER FOR OIL-BURNERS.

SPECIFICATION forming part of Letters Patent No. 744,453, dated November 17, 1903.

Application filed April 18, 1903. Serial No. 153,239. (No model.)

To all whom it may concern:

Be it known that I, HUGHY PERCYVILL AKERS, a citizen of the United States, and a resident of Crisman, in the county of Porter 5 and State of Indiana, have invented a new and Improved Spreader for Oil-Burners, of which the following is a full, clear, and exact description.

The invention relates to railroad signal-lamps and the like; and its object is to provide a new and improved spreader for oil-burners which is simple and durable in construction, very economical in the use of oil, and arranged to properly spread the flame 15 without causing smoke and without allowing dirt to accumulate in the spreader.

The invention consists of novel features and parts and combinations of the same, as will be more fully described hereinafter and 20 then pointed out in the claims.

A practical embodiment of the invention is represented in the accompanying drawings, forming a part of this specification, in which similar characters of reference indicate corresponding parts in all the views.

Figure 1 is a perspective view of the improvement as applied. Fig. 2 is a sectional side elevation of the same on the line 2 2 of Fig. 3. Fig. 3 is a transverse section of the 30 same on the line 3 3 of Fig. 2, and Fig. 4 is a face view of the blank for forming the spreader.

From the top of the body A of a lamp-burner of any approved construction rises a wick-tube B, onto which fits snugly the tubular shank C of the spreader, made from a single blank sheet of metal, as shown in Fig. 4. The blank has an apertured center portion, which forms the top D of the spreader, and the ends 35 of the center portion terminate in keystone-shaped flanges, which form the inclined sides E of the spreader and which sides extend upwardly and outwardly from the upper ends of the shank C, formed by the end pieces of 40 the blank bent into tubular shape. From the front and rear edges of the top D depend integral front and rear flaps F, in close proximity at their inner faces to the lower ends of the sides E (see Fig. 3) to form with the lat-

ter and with the upper ends of the shank C 50 openings for the ready admission of air to the burning wick at the upper end of the wick-tube B. The openings referred to also permit any dirt that may get into the spreader to readily drop out of the same to the ground, 55 so that accumulation of dirt in the spreader is completely prevented.

The width of the opening D' in the top D is approximately equal to the diameter of the round wick used in the wick-tube B; but the 60 said opening is elongated in the direction of the sides E to cause the flame to spread, and thereby produce an exceedingly bright light, especially as sufficient air passes to the burning wick to insure complete combustion, and 65 thereby prevent smoke.

It is understood that the construction described forms a cup-shaped spreader having air-admission openings between the sides E and depending flaps F and at the upper end 70 of the shank C, so that air readily passes to the flame to insure complete combustion and to allow any dirt that may pass into the spreader to readily drop through the openings, so as not to accumulate in the spreader. 75

The device can be very cheaply manufactured and readily applied to the ordinary railroad signal-lamps and the like.

Having thus described my invention, I claim as new and desire to secure by Letters 80 Patent—

1. A spreader for lamp-burners, formed from a single-piece blank and having a tubular shank, sides extending upwardly and outwardly from the upper ends of the shank, an 85 apertured top connecting the sides with each other, and front and rear flaps depending from the top, as set forth.

2. A spreader for lamp-burners, comprising a tubular shank, keystone-shaped sides extending upwardly and outwardly from the upper ends of the shank, a top connecting the sides with each other and provided with an elongated opening, and front and rear flaps depending from the top, as set forth. 90

3. A spreader for lamp-burners, comprising a tubular shank, keystone-shaped sides extending upwardly and outwardly from the

upper ends of the shank, a top connecting the sides with each other and provided with an elongated opening, and front and rear flaps depending from the top and abutting with their inner faces against the lower base ends of the said sides, as set forth.

5 In testimony whereof I have signed my

name to this specification in the presence of two subscribing witnesses.

HUGHY PERCYVILL AKERS.
